UNITED STATES PATENT OFFICE.

ADAM L. L. NEUMANN, OF OCCIDENTAL, CALIFORNIA.

WHIP-HOLDER.

1,173,533.

Specification of Letters Patent.

Patented Feb. 29, 1916.

Application filed February 24, 1915. Serial No. 10,374.

To all whom it may concern:

Be it known that I, ADAM L. L. NEUMANN, a citizen of the United States, residing at Occidental, in the county of Sonoma, State of California, have invented 5 certain new and useful Improvements in Whip-Holders; and I do hereby declare the following to be a full, clear, and exact description of the invention, such as will enable others skilled in the art to which it 10 appertains to make and use the same.

The present invention relates to certain novel and useful improvements in whip holders, and has particular application to a 15 device of this class wherein a whip socket is provided with certain whip engaging devices which are adapted to lock the whip in the socket.

In carrying out my invention I propose to 20 provide a whip socket equipped with certain whip engaging and holding devices which, when the butt end of the whip has been inserted in the socket, are adapted to clamp and hold the same until such devices are 25 moved to whip releasing position by the employment of a key manually operated by the driver or other person.

Still a further object of my invention is 30 the provision of a whip holder wherein the whip engaging and locking devices are concealed within the whip socket, and such devices can only be operated through the medium of a key so that the removal of the whip from the socket by unauthorized persons, or the accidental loss of the same by 35 falling out of the socket is prevented.

I also propose to provide a whip holding 40 device having a swinging jaw normally held in such position by a spring tensioned 45 wedge, that such jaw, while permitting the entrance of the blunt end of the whip to the socket, will prevent the withdrawal of such end therefrom until the jaw is moved away from the butt of the whip by the operation of the wedge when the latter is shifted by a key.

Furthermore, I propose to provide a whip 50 holder which will embody the desired features of simplicity, efficiency, reliability and convenience, and embodying as it does but relatively few parts, may be manufactured and marketed at a comparatively low cost.

With the above recited objects and others 55 of a similar nature in view, my invention consists in the construction, combination and

arrangement of parts set forth in and falling within the scope of the appended claims.

In the accompanying drawings: Figure 1 is a vertical longitudinal sectional view taken through a whip holder embodying my 60 invention, and showing a whip held therein. Fig. 2 is a cross sectional view taken on the line 2—2 of Fig. 1. Fig. 3 is a vertical sectional view taken through the casing and showing the device in whip releasing position when operated by a key. Fig. 4 is a 65 detail perspective view of the wedge for actuating the pivoted clamping jaw.

Referring now to the accompanying drawings in detail, the letter A indicates the 70 usual tubular whip socket having the ordinary flexible guard B at the top thereof, while C designates the butt end of the whip having the usual ferrule D at the end 75 thereof.

My improved whip holder includes an elongated U-shaped frame E, the parallel sides 1 and 2 of which are riveted to the inside of the vertical wall of the socket adjacent the upper end thereof, while the cross bar or bight 3 of the frame may be screwed to the bottom of the socket. This frame is preferably made of metal, and fastened to the side 2 thereof as at 4, is a bowed plate spring 5, the lower end of this spring being 80 free or unattached. In the present instance this plate spring is bent transversely so that it is of approximately V-shaped form with the apex 6 constituting a shoulder beneath which the upper end of the ferrule D is 85 adapted to engage when the whip is inserted in the socket, but I wish it to be understood that this spring may be of any suitable character, and if desired the whip contacting face of the spring 5 may be roughened to 90 more securely engage the whip.

The side 1 of the frame E is provided with longitudinally extending inwardly inclined flanges 7—7, and above these flanges I provide a pair of laterally and inwardly extending lugs 8, while 9 designates a plate 100 suitably fastened to the inner face of the side 1 of the frame and extending above and below the lugs 8. This plate 9 is bent centrally and longitudinally as at 10 so that it 105 forms a key-way or slot 11 in conjunction with the adjacent portion of the side 1 for the reception and passage of the key K, as hereinafter described. The lugs 8 are preferably located substantially diametrically 110

opposite to the point of fastening of the plate spring 5, and I hinge to these lugs a whip-locking jaw F. This jaw comprises a substantially rectangular plate having its 5 longitudinal edges bent rearwardly and inwardly to form flanges 12, the upper ends of the flanges being extended in parallelism to form ears 13 by means of which and the pintles 14 the jaw is hinged to the lugs 8. 10 The whip confronting face 15 of the jaw is longitudinally depressed or grooved to more readily accommodate the whip, and the lower free end of the jaw is cut inwardly or concaved as at 16 to snugly fit the butt of 15 the whip at the top of the ferrule.

The wedge employed for operating the whip-clamping jaw is shown in detail in Fig. 4 and is indicated as an entirety by the letter W. This wedge comprises a head from 20 which extends a shank 18. The head has a substantially flat face 19 which rides against the inner face of the side 1 of the frame E and a beveled top face 20 which is slightly concaved as shown at 21 to bear 25 against the back face of the clamping jaw. The sides of the head are provided with longitudinally extending V-shaped grooves 22 which form the lower flanges 23 that lie beneath the inclined flanges 7-7 of the side 30 1 of the frame E, and the upper flanges 24 which lie beneath the longitudinal flanges 12 of the clamping jaw. A coiled expansion spring 25 is connected at its upper end with the shank of the wedge and has its lower 35 end anchored as at 26 to the cross bar or bight of the U-shaped frame E.

As will be seen by reference to the drawings, the head of the wedge is arranged to slide between the side 1 of the frame and the 40 clamping jaw, being guided by the flanges 7 and 12, and the normal tendency of the spring is to push the wedge upward so that the clamping jaw will be forced outward. The key K is intended to be used for the 45 purpose of depressing or forcing the wedge downward against the action of the spring, such wedge in its downward movement drawing the clamping jaw outward or away from the whip, because it will be noted the 50 upper flanges 24 of the wedge interlock with the flanges 12 of the clamping jaw.

From the above description, taken in connection with the accompanying drawings, the construction and manner of employing my invention will be readily apparent. Assuming the whip holding device to be mounted in the socket as hereinbefore described, the driver on inserting the butt end

of the whip in the socket pushes outward or flattens the spring 5 so that the ferrule or 60 bead at the butt of the whip may be forced past the shoulder 6 of the spring 5 and the free end of the clamping jaw. When this takes place the clamping jaw will be moved inward again by the action of the coil spring 65 pushing the wedge upward and the spring 5 will, of course, return to its normal position. The whip will now be locked in the socket as shown in Fig. 1, and when it is desired to release the whip it is necessary to insert 70 the shank of the key K into the key-way or slot 11 and push the wedge down against the action of the coil spring, this downward movement of the wedge drawing the clamping jaw outward or toward the side 1 of the 75 frame E, thus permitting the whip but' to be pulled from the socket.

It will be noted that I have provided a simple, yet efficient and positive lock which will firmly clamp the whip in the socket and 80 thus prevent the whip being stolen or lost, for it will be noted that the lock can only be released by using the key, which may be carried by the driver.

While I have herein shown and described 85 one particular embodiment of my invention, I wish it to be understood that I do not confine myself to all the precise details of construction herein set forth by way of illustration, as modification and variation may 90 be made without departing from the spirit of the invention or exceeding the scope of the appended claim.

What I claim is:

The combination with a whip socket, of a 95 frame located therein, a leaf spring fastened at one end to one side of the frame, a clamping jaw hinged to the opposite side of the frame, a wedge slidingly engaging the clamping jaw and the side of the frame to 100 which it is hinged, said wedge normally tending to move the clamping jaw into whip engaging position, a spring acting to move the wedge to force the clamping jaw into wedge engaging position, and a key- 105 way adapted to permit the insertion of the key to move the wedge against the action of the spring and cause said wedge to withdraw the clamping jaw from whip engaging position.

In testimony whereof, I affix my signature, in the presence of two witnesses.

ADAM L. L. NEUMANN.
